Primary Examiner — Keli L Hill*Assistant Examiner* — Sara S Sahneh(74) *Attorney, Agent, or Firm* — Andrew F. Young, Esq.; Nolte Lackenbach Siegel(57) **CLAIM**

The ornamental design for a progressive tooth wrench, as shown and described.

DESCRIPTION

FIG. 1 is a front perspective view of a design for my progressive tooth wrench.

FIG. 2 is a left side elevation view of FIG. 1.

FIG. 3 is a right side elevation view of FIG. 1.

FIG. 4 is a front side elevation view of FIG. 1.

FIG. 5 is a rear side elevation view of FIG. 1.

FIG. 6 is a top plan view of FIG. 1; and,

FIG. 7 is a bottom plan view of FIG. 1.

The dash-dot-dash broken lines illustrate the boundaries of the claimed design. The dash-dash broken lines depict portions of the progressive tooth wrench and forms no part of the claimed design.

1 Claim, 5 Drawing Sheets(56)
